BEVATRON ACCELERATION REGULATION

George M. Farly, Berkeley, Calif., assignor to the
United States of America as represented by the
United States Atomic Energy Commission

Application January 5, 1951, Serial No. 204,616

8 Claims. (Cl. 250—27)

1

The present invention relates generally to an electronic frequency control system and in more particular to the control of the accelerating voltage in a particle accelerator.

Modern emphasis upon nuclear research has directed a large amount of effort to the development and improvement of particle accelerators. The need is for higher energy particles with which to carry out bombardment experiments and conventional limitations upon maximum energies that may be imparted to free subatomic particles has constituted an obstacle of no mean proportions. While numerous highly successful particle accelerators have been developed, as for example cyclotrons and synchrotrons, the need still remains for apparatus capable of imparting even greater energies to particles. One recent development in this field is an apparatus called a bevatron and disclosed in the copending application of W. M. Brobeck et al., Serial No. 196,048, filed November 16, 1950 an abstract of which was published January 30, 1951, in the Official Gazette of the United States Patent Office, 642 O. G. 1480. As will be appreciated from a reference to this application, the mode of acceleration requires a precise control of the accelerating voltage which is even more exact than in conventional accelerators. The present invention is adapted to provide the requisite accuracy of control of the accelerating voltage of a particle accelerator of the bevatron type and does so by the accomplishment of the following objects.

It is an object of the present invention to provide an improved method and means for controlling the accelerating voltage of a particle accelerator.

It is another object of the present invention to provide an improved method and means of frequency modulating the accelerating voltage of a particle accelerator.

It is another object of the present invention to provide an improved method and means for initiating and terminating the application of an accelerating potential in a particle accelerator.

Many other objects and advantages of the present invention will become apparent to those skilled in the art from the following description taken together with the attached drawings, wherein:

Figure 1 shows a bevatron particle accelerator with associated equipment including the present invention;

Fig. 2 shows one preferred embodiment of the present invention in block form; and

2

Fig. 3 shows a typical magnet field pulse as employed in a bevatron and having indicia thereon referenced to periods during one cycle of bevatron operation.

Considering first a particle accelerator with which the present invention may be advantageously associated, reference is made to Fig. 1 wherein there is shown a bevatron as an example of such an accelerator. As shown in Fig. 1 the bevatron includes four arcuate electromagnet sections 11, which are hollow and encompass arcuate tubular elements 12. Magnet sections 11 are arranged in a roughly circular fashion with straight tubular sections 13, 14, 15, and 16 interposed one between each magnet section and connected to the tubular elements 12 at each end thereof to form a continuous chamber 17. Electromagnet sections 11 are wound in such a manner that upon energization they produce magnetic flux in a direction normal to the plane of Fig. 1 and consideration of bevatron theory shows that the electrical geometry of the bevatron is not affected by straight sections 13-16. These sections are inserted in order to provide access to the interior of chamber 17 without interference with the magnet structure and vacuum pumps 18 are connected to sections 13-16 for the purpose of establishing and maintaining a high vacuum in chamber 17. Also connected to chamber 17 is an injector mechanism 19 which may consist of a small cyclotron 21 having deflecting means 22 leading therefrom into straight section 13; an outlet port 23 which may be inserted in section 14; and as shown in Fig. 2 accelerating means 24 which may be mounted within section 16.

Also included in the composition of a complete bevatron is a magnet current source 26 which may be connected through electrical leads 27 and 28 to the windings of electromagnet sections 11. Current source 26 must provide a very large amount of pulsed current in order to produce within electromagnet sections 11 the requisite magnet field intensity and may comprise a motor generator set having energy storage means whereby large quantities of electrical energy may be received as well as transmitted, all of which is explained in more detail below. An accelerating voltage source and regulator 29 is also provided for the energization of accelerating means 16 and in connection therewith there is included a current source 31. Voltage source 29 is interconnected with the windings of electromagnet sections 11 by means of a low resistance shunt 32 inserted in series in one of the electromagnet

leads 27 and which is also connected across terminals 33 of voltage source 29. There is also provided a pair of peaking strips 36 and 37 disposed adjacent electrical lead 21 and connected across terminals 38 and 39 respectively of voltage source 29.

Considering now the voltage source or the accelerating voltage regulator 29, as shown in Fig. 2, it will be noted that terminals 33, which are connected externally to shunt 32, lead to an amplifier 101 which amplifies the voltage signal produced across shunt 32. In addition, amplifier 101 contains a mixer circuit noted in more detail below. The amplified signal from shunt 32 is fed into a current regulator 102 which may in part comprise a losser tube connected in series between external current source 31 and control windings 103 of a saturable reactor 104. Of course the mode of current regulation is not critical and numerous arrangements may be employed to regulate the magnitude of the direct current voltage applied to windings 103. Saturable reactor 104 is employed as a variable inductance controlled by the magnitude of the direct current voltage applied to the control windings 103 thereof. In composition, saturable reactor 104 may consist of conventional apparatus or may include a core 106 of ferromagnetic non-metal having control windings 103 and impedance windings 107 which may be separate as shown or may alternatively be combined into a single winding in the manner disclosed in the copending application of Robert L. Anderson, Jr., Serial No. 191,304, filed October 20, 1950. It is desirable to prevent feedback of high frequency signals into the direct current control equipment and this may be accomplished by employing two balanced control windings connected to cancel out voltages induced therein or, in the case of single winding saturable reactors may be accomplished by employing two reactors, with the direct current connections being reversed so that cancellation of induced voltages therein is effected. Impedance windings 107 of reactor 104 have a capacitance 108 connected in shunt therewith to form the tank circuit of an oscillator tube 109, which has its anode connected through a capacitance 111 to one side of the tank circuit and its cathode to the other. Oscillator tube 109 is controlled by a multivibrator 112 whose output is impressed upon the control grid of tube 109 and which in turn obtains control signals from above noted peaking strips 36 and 37 through terminals 38 and 39, respectively. Grid excitation for oscillator tube 109 is obtained from a feedback coil 113 connected to one end of saturable reactor winding 107 and through a capacitance to a grid of tube 109. Plate supply for tube 109 may be provided either by an internal or external power supply, the details of which are of no importance and which is consequently indicated only as a + on Fig. 2. The output of the oscillator is applied via a feed through insulator 25 to the accelerating electrode 24 in bevatron section 16. There is further provided a discriminator circuit 114 which has an input lead connected to a tap on the impedance winding 107 of saturable reactor 104 and which applies a signal to the mixer circuit of amplifier 101.

Rather than further described the components of the accelerating voltage regulator by recitation as above, consideration will now be given to the operation of the invention, together with general bevatron operation as pertinent, and therein further defining the composition and function of

the composite elements. In conjunction with the description of operation, reference is made to Fig. 3 showing a typical bevatron magnet current pulse and including time indicia corresponding to changes between individual phases of operation within one cycle of operation of a bevatron.

In operation of a bevatron the chamber 17 thereof is evacuated by means of vacuum pumps 18 and all included power supplies are energized. Energization of the electromagnet sections 11 is then initiated by switchgear integral with magnet current source 26. At this time (T₁) no particle injection is taking place and no accelerating voltage is applied. After a short interval, during which the magnet field increases from zero to some small desired intensity, particle injection is commenced from cyclotron 21 through deflector 22 or by other suitable means. At the same time (T₂) accelerating voltage is applied to accelerating means 24 as described in more detail below. Particle injection continues for only a relatively short period from T₂ to T₃; however, acceleration of the injected particles continues for the greater part of the period during which the magnetic field is increasing, T₂-T₄ on Fig. 3. This accelerating voltage is regulated in relation to the magnetic field strength by accelerating voltage source and regulator 29 to maintain the mean particle orbit within chamber 17 and upon termination of acceleration (T₄) a further increase in magnetic field reduces the radius of the particle orbit so that the particles bombard a target, not shown, which may be mounted upon the inner wall of one of the tubular members 12 in line with outlet port 23 whereby high energy neutrons pass therethrough. The magnet current thereupon is decreased and the energy stored within the magnet windings may be advantageously returned to the magnet current source and stored therein by means such as a flywheel; the magnet current and magnet field reducing thereby to zero and completing one cycle of bevatron operation. It will be appreciated that variations in the operating cycles may be employed, as for example retarding the application of accelerating voltage until the cessation of particle injection; however, the choice of same is dependent upon design considerations unrelated to the present invention and are therefore only noted herein.

The present invention accomplishes control of the initiation and cessation of the application of accelerating voltage by means of signals obtained from the magnet field current rather than by direct time control. The more obvious method wherein phases of operation are referenced to a time base is limited by the difficulty in precisely regulating the magnet field pulses because of their extreme magnitude, and the present system is advantageous in controlling accelerating voltage in accordance with the actual disposition of the particles as determined by the magnetic field rather than by the calculated disposition of the particles based upon a time-field relationship which is in fact variable. The control signals in the present embodiment are obtained from magnetic peaking strips 36 and 37, one of which, for example strip 36, is designed to saturate at a magnet field strength corresponding to the magnet field current at T₂ on Fig. 3 and to thereby provide a voltage pulse across terminals 38, and the other strip 37 is designed to saturate at a much higher magnet field strength corresponding to the magnet field current at T₄ on Fig. 3, thereby providing a second voltage pulse which appears across terminals 39. As

shown in Fig. 2, terminals 38 and 39 are both connected to multivibrator 112 which may constitute a conventional one shot multivibrator operating upon a single pulse to initiate operation and a single pulse to cease operation. Oscillator tube 109 is biased to cutoff by appropriate potentials applied thereto and thus the oscillator has no output until the signal from peaking strip 36 causes multivibrator 112 to operate and thereby apply a signal to the grid of oscillator tube 109 which initiates operation of the oscillator (T₂ on Fig. 3). Oscillator operation continues until the magnet field current reaches some predetermined value (T₄ on Fig. 3), at which time peaking strip 37 applies a second signal to multivibrator 112 which turns it off, thereby returning oscillator tube 109 to a non-conducting state and ceasing the operation of the oscillator. During this period, T₂ to T₄, accelerating electrode 24 is energized by the oscillator output.

In addition to the above-noted control of the portion of the magnet field cycle during which particles are accelerated it is further necessary to regulate the application of the accelerating voltage in such a manner that the particles are in fact accelerated rather than decelerated as would result from an improper phasing of the accelerating voltage. As the particles travel about their orbit with increasing velocity they approach any particular point, such as the point of acceleration, at increasingly shorter intervals of time and the accelerating voltage must be pulsed at the proper time to attract the particles so approaching. Proper timing of the accelerating voltage pulses is accomplished by frequency modulation of the accelerating voltage and this, too, is based upon the instantaneous magnet field current rather than upon a time relationship which is susceptible to variations as noted above. The low resistance shunt 32 provides a voltage signal proportional to the magnet current and this signal is impressed across terminals 33 of amplifier 101. The strength of this signal is increased by amplifier 104 which applies the amplified signal to the control circuit of current regulator 102, which in turn regulates the output of current supply 31 in accordance with the applied signal. This regulated current from power supply 31 is applied to the direct current windings 103 of saturable reactor 104 and by varying the saturation of the core 106 thereof consequently controls the impedance of the alternating current windings 107. As windings 107 of saturable reactor 104 are connected together with capacitor 108 to form the tank circuit of oscillator tube 109 there is formed in effect an oscillator having a variable inductance and whose frequency of oscillation is controlled by the current applied to the direct current windings 103 of saturable reactor 104. As the inductance in the tank circuit of the oscillator is controlled by the magnet field current, the frequency of the accelerating voltage output of the oscillator is thereby modulated in accordance with the magnet field current.

The above frequency modulation system relates the accelerating voltage to the magnet field strength by way of the magnet field current; however, it will be appreciated that the relationship obtained by direct control of the frequency with the magnet current may not be the one desired for the particular bevatron operation contemplated. For example, a linear relationship between the magnet current and the frequency of the acceleration voltage may be desired, while the saturation characteristics of reactor 104 may

well produce some other relationship. Thus modification of the frequency control as described above is ordinarily necessary, and this may be accomplished either by utilizing a specially designed saturable reactor having the requisite saturation characteristics or by introducing a correction signal into the system to compensate for the deviation from the desired relationship. The illustrated embodiment of the invention employs the latter of the two above suggested alternatives in preference to the complexities of reactor design necessitated by the first, and further in view of the flexibility afforded by systems competent to introduce corrective signals. As shown in Fig. 2, a discriminator 114 is employed for the purpose of supplying a corrective feedback signal. The discriminator input signal is obtained from the tank circuit of oscillator tube 109 by means of connection to a low voltage tap on the impedance winding 107 of reactor 104 and the discriminator output signal is applied to a mixer circuit in amplifier 104 wherein it is algebraically added to the original control signal from shunt 32 in magnet winding lead 27. The amplified control signal applied to current regulator 102 is thus compensated so that the saturating current of reactor 104 produces the requisite inductance variation in the tank circuit of the oscillator and the frequency of the accelerating voltage therefrom has the desired relation to the magnet field. The discriminator circuit may be designed in a conventional manner well known to those skilled in the art although it, like the other conventional circuits shown in block form, may alternatively be particularly designed for specific results required in an individual application.

From the foregoing it is believed evident that the present invention is capable of providing precise accelerating voltage control for a device such as a bevatron, and that the system employed for accomplishing this result is free from the difficulties and errors either inherent to or introduced into conventional regulating means employed in such as capacity as the present invention. While the invention has been disclosed with respect to but a single preferred embodiment, it will be apparent to those skilled in the art that numerous variations and modifications may be made within the spirit and scope of the invention and thus it is not intended to limit the invention except as defined in the following claims.

What is claimed is:

1. In a bevatron having magnet windings energized through electrical conductors from a current source and electrostatic accelerating means, the combination comprising an oscillator energizing said accelerating means and having a variable inductance in the tank circuit thereof, means connected into said electrical conductors for developing a voltage proportional to current flow therethrough, and control means connected between said last-named means and said variable inductance whereby the frequency of said oscillator is varied in accordance with the value of the magnet current.

2. In combination with a bevatron having magnet windings energized through electrical conductors and electrostatic particle accelerating means, an improved control system including an oscillator having a tank circuit with a variable inductance therein and impressing the output voltage thereof upon said accelerating means, inductance control means associated with said variable inductance and controlling the fre-

quency of said oscillator by controlling the inductance of the tank circuit thereof, a resistance shunt connected in series with one of said magnet winding conductors, and electrical connections impressing the voltage signal across said shunt upon said inductance control means whereby the frequency of the voltage impressed upon said accelerating means is controlled by the current through the conductors to said magnet windings.

3. In combination with a bevatron having a magnetic field established by electromagnet windings energized through electrical conductors from a current source and electrostatic particle accelerating means, the improvement comprising an accelerating voltage frequency control system including an oscillator circuit electrically connected to said accelerating means for impressing an accelerating voltage thereon, said oscillator circuit including an oscillator tube having a control electrode and an associated tank circuit having a variable inductance therein for varying the frequency of the oscillations, inductance control means having an input circuit including a resistance shunt connected in series with one of said electromagnet conductors and controlling said variable inductance in said oscillator tank circuit to control the frequency of the voltage impressed upon said particle accelerating means in accordance with the current flow to said electromagnet, and a pair of current responsive means associated with said electromagnet conductors and connected to said oscillator tube control electrode to initiate and cease operation of said oscillator in accordance with the magnitude of current flow to said electromagnet.

4. In combination with a bevatron having an evacuated chamber within the poles of an electromagnet having windings energized from a current source and particle injection and acceleration means, the improvement comprising an accelerating voltage frequency control system connected to said particle accelerating means and including an oscillator circuit having an oscillator tube with a control electrode and a tank circuit comprising a capacitor and inductor, said inductor having inductance windings and control windings wound about a magnetic core, current supply means connected to and energizing the control windings of said inductor, a resistance shunt connected in series with said electromagnet windings, and electronic control means connected across said shunt and to said current supply means to vary the current to said inductor control windings as a function of the current to said electromagnet windings whereby the inductance of the inductance windings of said inductor and consequently the frequency of said oscillator is varied as a function of the current to said electromagnet.

5. In combination with a bevatron having an evacuated chamber within the field of an electromagnet and particle injection and acceleration means, the improvement comprising an oscillator connected to said particle accelerating means and impressing thereon a high frequency voltage, said oscillator including a capacitor and a current responsive inductor connected in parallel in a tank circuit, said inductor having a control winding and an effective inductance proportional to the current through said control winding, and current supply means producing a current proportional to the current through said electromagnet and connected to said inductor

control winding whereby the effective inductance thereof and consequently the frequency of said oscillator voltage is varied in proportion to said electromagnet current.

6. An accelerating voltage control system for a bevatron having an accelerating electrode and magnet windings energized from a current source through conductors and comprising an oscillator vacuum tube having an anode, cathode, and control electrode with the anode thereof connected to the accelerating electrode of said bevatron, a saturable reactor having control and induction windings, a capacitor connected across said induction windings and between the anode and cathode of said vacuum tube to define a tank circuit therefor, a current source, a current regulator connected between said current source and the control windings of said saturable reactor, a resistance shunt connected in series with a magnet winding conductor and to said current regulator to impress thereon a voltage proportional to the magnet winding current whereby the current to said saturable reactor control windings and thus the inductance of said inductance windings is varied in accordance with the magnet winding current to control the oscillator tube frequency, a multivibrator connected to the control electrode of said oscillator vacuum tube, and a pair of peaking strips disposed adjacent the magnet winding conductor and connected to said multivibrator to initiate and cease operation of said multivibrator and attached oscillator vacuum tube at predetermined values of magnet winding current.

7. An accelerating voltage control system for a bevatron having magnet windings energized through conductors to establish a magnetic field and an accelerating electrode for imparting energy to particles traveling in said magnetic field, said accelerating voltage control system comprising an oscillator circuit including an oscillator vacuum tube having a control electrode and a tank circuit including a saturable reactor having control and inductance windings, means connecting said oscillator circuit to said bevatron accelerating electrode to energize same, a current source, a current regulator connecting said current source to the control windings of said saturable reactor, an amplifier and mixer circuit connected to said current regulator and impressing a control signal thereon, a resistance connected in a magnet winding conductor and being connected to said amplifier and mixer circuit to impress thereon a voltage proportional to the magnet winding current, a discriminator circuit connected between said amplifier and mixer circuit and a point on the inductance winding of said saturable reactor whereby the current to said saturable reactor control windings and thus the frequency of said oscillator circuit is controlled in accordance with the magnet winding current as modified by said discriminator circuit signal.

8. An accelerating voltage control system as claimed in claim 10 further defined by a first magnetic peaking strip which is saturable at a predetermined low magnet field strength, a second magnetic peaking strip which is saturable at a predetermined high magnetic field strength, said first and second peaking strips being disposed adjacent the magnet winding conductor having said resistance shunt connected therein, a multivibrator circuit having an output circuit connected to the control electrode of said oscillator tube to energize same and an input cir-

9

cuit connected across said peaking strips where-
by initiation and cessation of operation of said
oscillator circuit is controlled in accordance with
the magnitude of magnet winding current.
